COIN HOLDER

Otto Mayer, R.F.D. 2, Lake Carmel, N.Y.

Filed Aug. 9, 1965, Ser. No. 86,511

Term of patent 14 years

(Cl. D87—3)

FIG. 1

FIG. 2

FIG. 4

I claim:

The ornamental design for a coin holder, substantially as shown.
